FIG. 8.

UNITED STATES PATENT OFFICE.

GULIELMO COTTINI, OF SPRINGFIELD, AND GIROLAMO COTTINI, OF LUDLOW, MASSACHUSETTS, ASSIGNORS TO MICHAEL T. FOLEY, OF SPRINGFIELD, MASSACHUSETTS.

PAPER-DISPENSING CABINET.

1,311,799.

Specification of Letters Patent. Patented July 29, 1919.

Application filed May 15, 1918. Serial No. 234,826.

To all whom it may concern:

Be it known that we, GULIELMO COTTINI and GIROLAMO COTTINI, both citizens of the United States of America, and residents, respectively, of Springfield, in the county of Hampden and State of Massachusetts, and Ludlow, in said county and State, have invented a new and useful Paper-Dispensing Cabinet, of which the following is a specification.

Our invention relates to boxes or cabinets for dispensing toilet-paper, paper towels, and the like, and consists essentially of a slotted receptacle designed to hold a plurality of sheets of paper and permit such sheets to be withdrawn one at a time, and of means whereby such sheets are enabled to be so withdrawn, such means comprising a movable member adapted to be actuated into a position to expose a part of the sheet to be withdrawn, so that such exposed part can be grasped with the hand, together with such auxiliary and subsidiary parts and members as may be necessary or desirable to make this device complete, all as hereinafter set forth.

It is necessary to use in our cabinet paper which is folded in a certain manner, as will presently appear.

Heretofore much difficulty has been experienced with paper-dispensing cabinets, due to the fact that the contents of such a cabinet, that is to say, the paper therein, was accessible from the outside and such paper or the package of the same was frequently overturned or otherwise displaced, by accident or design, with the result that the proper functioning of such cabinets was seriously interfered with and even interrupted altogether. And the primary object of our invention is to provide a cabinet of this kind which protects the contents from outside manipulation or interference, thus obviating the aforesaid objections and difficulties and insuring a proper delivery or feed at all times.

A further object is to produce a cabinet, which, besides possessing the above-mentioned important, valuable, and advantageous feature or element of safety, is capable of dispensing individual sheets of paper from a stack or pile, and of doing so until the last sheet is taken.

Still another object is to produce a cabinet which is comparatively inexpensive, is sim-

ple in construction and operation, has few or no parts that are liable to break or get out of order, and is withal highly efficient, practicable, and serviceable.

Other objects and advantages will appear in the course of the following description.

A preferred form or embodiment of the invention, whereby we attain the objects and secure the advantages of the same, is illustrated in the accompanying drawings, and we will proceed to describe said invention with reference to said drawings, although it is to be understood that the form, construction, arrangement, etc., of the parts in various aspects are not material and may be modified without departure from the spirit of the invention.

In the drawings, in which like numerals designate like parts throughout the several views, Figure 1 is a front elevation of a paper-dispensing cabinet which embodies a practical form of our invention as aforesaid; Fig. 2, a horizontal section through said cabinet, the door being shown open, while in the other views where said door appears it is shown closed, or in closed position; Fig. 3, a transverse, vertical section through the cabinet, taken on lines 3-3, looking in the direction of the associated arrow, in Fig. 2; Fig. 4, an enlarged detail of the lower portion, which includes practically all of the working parts and members, of said cabinet, in transverse section, showing several properly folded sheets of paper in place ready to be dispensed; Fig. 5, a similar view to Fig. 4, but showing the dispensing slide pushed back and the bottom sheet of paper in readiness for withdrawal, this and the preceding view being operative views; Fig. 6, a sectional view of a modification of the cabinet, the section being taken just inside of the end which is nearest the beholder; Fig. 7, a sectional view of still another modification, this section being taken close to the end which is the more remote from the beholder; Fig. 8, a top plan of said slide, a portion being broken away at the right-hand end, and, Fig. 9, an enlarged isometric view of the finger-controlling lug.

Our receptacle, box, or cabinet proper preferably consists of end pieces 1-1 the upper rear corners and the lower and front corners of which are right-angles, the lower rear corners of which are acute-angles, and

the upper front corners of which are obtuse-angles; an oblique back side 2 which forms a right-angle with the bottom plane of said end pieces; a top 4 which is flush 5 with the upper edges of said end pieces, all three being horizontal; a wide bottom or floor plate 5 which is flush with the bottom edges of said end pieces, and in the present case extends from the bottom rear corners 10 of said end pieces forward about one-third of the distance between said back side and the front edges of said end pieces, and a narrow bottom or floor plate 6 which is on a plane that is higher than but parallel with 15 the plane of said first-named plate, a slot or opening of considerable width thus being left between adjacent edges of said plates; and a base piece 7 across the front, to which a door 8 is hinged at 9—9, said 20 base piece being flush with the front edges of said end pieces, and said door, when closed, extending up to the front edge of said top. The several fixed parts and members just described are fastened together in 25 any suitable and usual manner, so, too, with reference to other rigidly connected parts and members hereinafter described. The foregoing description relates to the box and parts thereof as they appear in the first five 30 views, and the cabinet as a whole in these views will be described before considering the modifications illustrated in Figs. 6 and 7.

This box is designed to be fastened against a wall or other vertical support by means 35 of screws passing through the back side 2, and the peculiar shape given the same is to throw up the bottom thereof or give it an upward and forward pitch so as to facilitate the withdrawal of the paper from the 40 box through said bottom, and at the same time provide for the proper accommodation of the paper within the box.

Locking means are provided for the door 8, such means here consisting of a staple 10 and a padlock 11. When the padlock 11 is removed from the staple 10, the door 8, if closed, can be turned downwardly and forwardly into the open position shown in Fig. 2. The paper is inserted in the box 50 through the doorway when the door is open, and then the latter is closed and locked.

Extending forwardly from the back side 2, over the bottom plate 5 and spaced therefrom, is a paper support 12, and extending rearwardly from the base piece 7, over the bottom plate 6 and spaced therefrom, is a paper support 13. These supports are both fixed members.

A dispensing slide 14 is arranged on the 60 plates 5 and 6, having front and rear portions that extend under the paper supports 13 and 12, respectively. The slide 14 at all times, that is, regardless of its position, covers or closes the slot or space between adjacent edges of the plates 5 and 6 to an ex-

tent that makes it impossible to pass the fingers through such opening and so reach the paper above, as will presently more clearly appear. The part of the slide 14 that rests and reciprocates on the plate 6, 70 and which is indicated by the numeral 15, is spaced from the part of said slide that rests and reciprocates on the plate 5, by means of end uprights 16—16. The space between the uprights 16 is long enough to 75 permit a sheet of paper to be drawn through the same, but said space is not of sufficient width for the passage of the fingers. For the purpose of steadyng and guiding the slide 14 two rivets 17 are passed through 80 the same number of openings 18 in said slide and two transverse or forwardly and rearwardly extending slots 19 in the plate 5. A handle 20 depends from the forward piece 15 of the slide 14, through a lateral or forwardly and rearwardly extending slot 21 in the transverse center of the plate 6. The under portion of the base piece 7 may be cut away adjacent to the handle 20, as shown at 22, and the middle portion 23 of the front 90 edge of the plate 6 and a tongue 24 which projects forward from the front edge of the part 15 extend beneath said under portion of said base piece, said tongue being above said middle portion 23.

When the slide 14 is in its forward position the handle 20 bears against the front end of the slot 21, and said slide is normally retained in such position by two springs 25. Each spring 25 has its front end attached to 100 the back side of the base piece 7, adjacent to one end of said base piece, and its rear end attached to a lug or hook 26 that extends downwardly from the adjacent end of the slide part 15, in front of the upright 16, at 105 that end. Upon grasping the handle 20 the slide 14 can be forced backwardly, against the resiliency of the springs 25, as far as the rear ends of the slots 21 and 19 will permit, and upon releasing said handle said springs 110 actuate said slide forward again into initial position, said handle and the rivets 17 sliding in their respective slots, and said slide on the plates 5 and 6 and beneath the paper supports 12 and 13.

Having its forward end pivoted at 27 to the underside of the slide part 15, behind the handle 20, is a finger 28. At the pivoted end of the finger 28 is a short, angularly-arranged lug 29. Both the finger 28 and the lug 29 extend through and below the slot 21. An angular lug 30, clearly shown in Fig. 9, is secured to the underside of the plate 6 and extends to the left into engaging relation with the finger 28 and its lug 29. When 125 the slide 14 is in the forward, normal position, the lug 30 bears beneath the finger 28 and retains it in elevated position, with the rear terminal of said finger against the under edge of the rear end of the slot 21 and 130

well above and clear of the bottom of the slot or opening, indicated by the numeral 40, between the plates 5 and 6 and between the uprights 16, as shown in Figs. 3 and 4. And, when the slide is moved rearwardly, the lug 30 is moved forward along the finger 28, encounters the lug 29, and tilts said finger downwardly past and below the horizontal plane of the bottom of the aforesaid slot or opening, as shown in Fig. 5.

The paper used in our cabinet is folded so as to form of each sheet a long lap and a short lap. Such paper so folded must be of a size to fit within the box and pass through the approximately vertical slot 40, in the slide 14. Each sheet is placed on the one below with the short lap underneath, and the proportion of the long and short laps are such that only the long laps rest on the support 13 above the part 15 and the floor plate 6, when the sheets are placed in the box with the folded edge portions on the support 12 above the lower, major portion of the slide 14 and the floor plate 5, which is the manner in which said sheets are placed in said box, while the short laps are in position to enable their forward portions to drop down onto the slide 14 behind the approximately vertical slot 40 therein. Thus the lap, of the folded sheet that rests directly on the supports 12 and 13, or that portion of said lap which is forward of the front edge of said support 12, drops down and wholly or partially rests on the slide 14 behind the slot 35 therein. This is fully illustrated in Fig. 4. In each of Figs. 4 and 5 a stack comprising a plurality of folded sheets is represented at 31, and the long and short laps of the bottom sheets are further designated by the numerals 32 and 33 respectively.

Two, approximately vertical, end guides 34 are provided for the stack of paper 31, to insure the proper placing of the paper in the box and the retention of said paper in proper position, so that the same can be drawn through the delivery slot in the slide 14. Each guide 34 is fastened at the upper end to the top 4. The slide 14 reciprocates freely under the bottom ends of the guide 34. The guides 34 are located, by the fastening means at the top and outwardly turned feet 35-35 at the bottom, far enough from the end pieces 1 to confine the paper well within the vertical planes of the inner edges 55 of the uprights 16.

Guides 36-36 and 37-37 are provided on the base piece 7 and the door 8, respectively, to prevent the paper from working forward, as the pile diminishes, and getting caught on the hinges 9 or in the crack between said base piece and door. The guides 36 are standing members secured on the inside of the base piece 7, and the guides 37 are similar members, when the door 8 is closed, secured to the inside of said door. The guides 36

and 37 in the two pairs are in offset relationship to each other, and the former project above the top of the base 8, consequently the paper cannot be caught between adjacent ends of said guides.

The parts of the paper support 12 that are over the slots 19 in which the rivets 17 travel are raised to enable the heads of said rivets to clear such parts, as represented at 38.

Ordinarily no weight or follower of any kind is required for the paper stack 31, but a weight or follower, such for example as I have shown at 39 in Figs. 4 and 5, may be provided if required or desired. The follower 39 is placed on top of the pile 31 and serves to press the sheets together and assist at all times in keeping them in a compact condition and the bottom of said pile and even the last remaining sheet thereof in close contact with the supports 12 and 13.

In operation, assuming that the pile of paper 31 is in place on the supports 12 and 13, first the slide 14 is forced rearwardly, by means of the handle 20, with the result that the short lap 33 of the bottom sheet in said pile, which was resting on said slide as shown in Fig. 4, is caused to project from the slot 40, and the finger 28 is caused to press the middle portion of the protruding part of said lap downwardly, as shown in Fig. 5; next said protruding and downwardly-pressed part or portion of said lap is seized and said bottom sheet drawn out of the box through said slot; and, finally, said slide is released to the springs 25 and by the latter returned to initial position. The slide 14 is manipulated with one hand and the paper pulled from the box with the other hand. When the slide 14 is pushed back it does not disturb the paper, since the latter is resting on the supports 12 and 13 and said slide operates beneath said supports, but the forward edge portion of the lap 33, which portion was lying on said slide directly behind the slot 40, is left protruding from said slot in readiness to be grasped. Upon grasping the exposed edge portion of the bottom sheet and drawing such portion forward, the remainder of said sheet follows easily, being first drawn without difficulty from between the support 12 and the pile at the rear, and then over the back edge of the part 15 and from between the support 13 and said pile at the front. No other sheet is disturbed during the operation or when the slide 14 is released to its springs and by them actuated forward, and the last sheet can be as readily dispensed in the manner just explained as the first. After the withdrawal of the sheet and upon the release of the slide the latter moves forward into place, and the short lap of what is now the bottom sheet drops onto said slide, behind the delivery slot 40, in readiness for the dispensing of said last-

130

named sheet, said lap having been previously held up against the pile first by the long lap 32 and then by the part 15.

The device is operative and practicable without the depressor members, which include the finger 28, but by employing such members the exposed edge of the paper is presented in a more convenient form for grasping with the thumb and fingers, since it is turned downward into a more accessible position. As the slide 14 moves backward the finger 28 slides along on the lug 30 until the lug 29 arrives at said lug 30, when said finger, which has meanwhile been swinging downwardly at the rear end, is thrust down positively, and the now protruding edge portion of the lap 33 is engaged by said rear end of said finger and turned downwardly. During the act of withdrawing the sheet the same is drawn from the delivery slot 40 at a pitch which insures clearance of the finger 28. Upon the forward return of the slide 14 the finger 28 is raised into inoperative position, in the manner previously explained.

It will be observed, as previously stated, that the opening between adjacent edges of the bottom plates 5 and 6 is always covered by the slide, no matter what the position of said slide may be, and that the only access to the interior of the box or paper receptacle, through the bottom or from below, is by way of the approximately vertical and comparatively narrow slot 40. Without the use of some special implement or instrument, therefore, the pile 31 of paper cannot be overthrown, disarranged, or otherwise interfered with from beneath.

Passing now to Figs. 6 and 7, it will be seen that, in the first of these views, the cabinet is so disposed that the paper is supplied at the top and dispensed through the front side, and, in the second of these views, the cabinet is so disposed that the paper is supplied at the front and dispensed through the top. With the exception of a lip 48 on the slide part 15 and the follower, the construction of either the Fig. 6 or the Fig. 7 cabinet is precisely the same as that of the first. In the Fig. 6 cabinet a follower 41, somewhat similar to the follower 39, is provided, with a pair of springs 42 to force said follower toward the dispensing front of the cabinet. In the Fig. 7 cabinet a follower 43, generally similar to the others, is forced upwardly against the paper by a pair of weights 44.

The springs 42 have their rear ends attached to the top 4, which has here become the back side of the box, and the front ends of said springs are attached to the follower 41. Similar springs might be used in place of the weights in the Fig. 7 cabinet, also with the follower 39 in any case when the force of gravity proved to be insufficient,

and it would be feasible to employ a weight or weights with either said follower 39 or the follower 41.

Projecting inwardly from each end 1, of the box, Fig. 7, are two studs 45, one in front of the other, mounted on each stud are two idlers 46, and a cord 47 passes over each of said idlers, such cord having one end fastened to the adjacent end of the follower 43, and having one of the weights 44 attached to the other end. The idlers 46 are located as high as possible at each end of the box, and at a sufficient elevation so that the forward part of the follower 43 can be drawn up into contact with the support 13 and the lip 48 above.

The lip 48 is provided, in each of the two modifications, to guide the short lap of the sheet being dispensed to the adjacent slot 40, when the slide 14 is actuated against the resiliency of its springs.

At 49 each end of the floor plate 6 is bent downwardly and outwardly to form a pocket for one of the springs 25.

What we claim as our invention, and desire to secure by Letters Patent, is—

1. In a paper-dispensing cabinet, a receptacle having an opening in one of its surfaces, and a reciprocable member covering such opening at all times, said member having therein a delivery slot for the passage of one end of a paper sheet, when said member is actuated out of initial position, and through which slot such sheet is drawn by hand.

2. In a paper-dispensing cabinet, a receptacle having an opening in one of its surfaces, a reciprocable member covering such opening at all times, and having therein a delivery slot for the passage of one end of a paper sheet, when said member is actuated out of initial position, and means to support the paper, with the exception of a loose part of the sheet in position for immediate delivery out of contact with said movable member, such loose part being the part that enters said slot.

3. In a paper-dispensing cabinet, a receptacle having an opening in one of its surfaces, a movable member covering such opening at all times, and having therein a delivery slot through which a part of a sheet of paper in said receptacle protrudes, when said movable member is actuated in one direction, and means to engage such protruding part and turn it away from adjacent parts of the cabinet.

4. In a paper-dispensing cabinet, a receptacle having an opening in one of its surfaces, and provided with paper-supporting means on opposite sides of such opening, and a slotted reciprocable member covering such opening at all times, and adapted to receive a loose part of a sheet of paper which bears directly on said supporting means, and

when actuated in one direction to project said loose part through the slot in said member, and to support the loose part of the next sheet, after the first sheet has been withdrawn, until said member is actuated in the other direction.

5. The combination, in a paper-dispensing cabinet, with a receptacle having front and rear floor members spaced apart and in stepped relationship, and paper supports extending over said members, of a sliding dispensing member comprising upper and lower parts which are received on said floor members under said supports, and having a delivery slot between adjacent edges of said upper and lower parts.

6. The combination, in a paper-dispensing cabinet, with a receptacle having front and rear floor members spaced apart and in stepped relationship, and paper supports extending over said members, of a sliding dispensing member comprising upper and lower parts which are received on said floor members under said supports, and having a delivery slot between adjacent edges of said upper and lower parts, and resilient means normally to retain said dispensing member at the forward end of its travel.

7. The combination, in a paper-dispensing cabinet, with a receptacle having front and rear floor members spaced apart and in stepped relationship, said front member being slotted, and paper supports extending over said members, of a sliding dispensing member comprising upper and lower parts which are received on said floor members under said supports, and having a delivery slot between adjacent edges of said upper and lower parts, and a handle extending down from said upper part of said dispensing member, through the slot in said front floor member.

8. The combination, in a paper-dispensing cabinet, with a receptacle having front and rear floor members spaced apart and in stepped relationship, and paper supports extending over said members, of a sliding dispensing member comprising upper and lower parts which are received on said floor members under said supports, and having a delivery slot between adjacent edges of said upper and lower parts, and means, between said lower part of said dispensing member and said rear floor member, to hold said dispensing member to its course.

9. The combination, in a paper-dispensing cabinet, with a receptacle having front and rear floor members spaced apart and in stepped relationship, and paper supports extending over said members, of a sliding dispensing member comprising upper and lower parts which are received on said floor members under said supports, and having a delivery slot between adjacent edges of said upper and lower parts, and means to depress

the portion of a sheet of paper which protrudes from said slot, when said dispensing member is actuated rearwardly.

10. The combination, in a paper-dispensing cabinet, with a receptacle having front and rear floor members spaced apart and in stepped relationship, and paper supports extending over said members, of a sliding dispensing member comprising upper and lower parts which are received on said floor members under said supports, and having a delivery slot between adjacent edges of said upper and lower parts, a finger pivotally attached to said upper part of said dispensing member in position to operate in front of said slot, said front floor member being slotted to accommodate said finger, and means to operate said finger.

11. The combination, in a paper-dispensing cabinet, with a receptacle having front and rear floor members spaced apart and in stepped relationship, paper supports extending over said members, and a lug attached to the underside of said front floor member, of a sliding dispensing member comprising upper and lower parts which are received on said floor members under said supports, and having a delivery slot between adjacent edges of said upper and lower parts, and a finger provided with a lug and pivotally attached to the upper part of said dispensing member in position to operate in front of said slot, said front floor member being slotted to accommodate said finger, and said first-named lug being in the path of said finger and its lug.

12. The combination, in a paper-dispensing cabinet, with a receptacle having front and rear floor members spaced apart and in stepped relationship, and paper supports extending over said members, of a sliding dispensing member comprising upper and lower parts which are received on said floor members, under said supports, and having a delivery slot between adjacent edges of said upper and lower parts, and springs arranged between the front of said receptacle, near the ends, and adjacent parts of said dispensing member, normally to retain the latter in its forward position.

13. In a paper-dispensing cabinet, a receptacle having front and rear floor members spaced apart and in stepped relationship, paper supports extending over said members, a sliding dispensing member comprising upper and lower parts which are received on said floor members under said supports, and having a delivery slot between adjacent edges of said upper and lower parts, and end guides arranged in said receptacle to keep the paper between the vertical planes of the ends of said slot.

14. In a paper-dispensing cabinet, a receptacle having front and rear floor members spaced apart and in stepped relation-

6
ship, paper supports extending over said members, a door in the front of said receptacle, a sliding dispensing member comprising upper and lower parts which are received on said floor members under said supports, and having a delivery slot between adjacent edges of said upper and lower parts, and guides on the front of said receptacle, including said door, to prevent the paper from 10 coming into contact with the closed front of the receptacle.

15. In a paper-dispensing cabinet, supporting means for the front and rear portions of sheets of paper folded to form long and short laps, and arranged with the short laps underneath, and a slotted sliding member, the short lap, of the sheet which is in direct contact with said supporting means, being in the path of the slotted part of said 20 sliding member, when the latter is in initial position, and adapted to be received in the slot and project from the same, when said member is actuated out of initial position.

16. In a paper-dispensing cabinet, supporting members spaced apart and in stepped relationship, for the front and rear portions of sheets of paper folded to form long

and short laps, and arranged with the short laps underneath, and a sliding slotted offset member spanning the gap between said supporting members, the short lap, of the sheet which is in direct contact with said supporting members, being in the path of the slotted part of said sliding member, when the latter is in initial position, and adapted to be received in the slot and project from the same, when said sliding member is actuated out of initial position.

17. In a paper-dispensing cabinet, a receptacle the bottom of which has a forward and upward inclination, and comprises front and rear paper-supporting members which are spaced apart, and a slotted sliding member adapted, when actuated in one direction, to expose through the slot therein a portion of the sheet of paper which is in direct contact with said paper-supporting members, said sliding member spanning the gap between said first-named members.
